Primary Examiner — Calvin E Vansant*Assistant Examiner* — Sydney M Evans(74) *Attorney, Agent, or Firm* — Polsinelli PC(57) **CLAIM**

The ornamental design for a barrier connection as shown and described.

DESCRIPTION

FIG. 1 is a perspective view of a barrier connection, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The shade lines in the Figures show contour and do not claim surface ornamentation or treatment.

1 Claim, 4 Drawing Sheets(56)
